UNITED STATES PATENT OFFICE

2,284,089

GLASS TUBE RESHAPING APPARATUS

Clarence E. Hahn, Euclid, and John Salo, Cleveland, Ohio, assignors to General Electric Company, a corporation of New York

Application October 20, 1939, Serial No. 300,382

7 Claims. (Cl. 49—7)

Our invention relates to apparatus for reshaping the ends of vitreous tubing and more particularly to automatic apparatus for reducing both ends of a vitreous tube simultaneously.

The principal object of our invention is to provide automatic apparatus for reshaping the ends of vitreous tubes, which apparatus may be easily adjusted to accommodate different lengths of tubing, and which is capable of operating both at faster speeds and with greater accuracy than possible heretofore. The apparatus comprising our invention is particularly useful for reshaping relatively large size tubing such as that used for the containers or envelopes for certain types of electric incandescent lamps and discharge lamps. Lamps of these types are manufactured in various lengths, and for purposes of economy it is desirable that a single apparatus accommodate all of these lengths. Because of the precise manufacture of such lamps, it is also desirable that the reshaping be performed under accurate control and, if desired, be confined to a very narrow rim portion of each end of the tube.

Other features and advantages of our invention will appear from the following detailed description of a species thereof and from the drawings.

In the drawings, Fig. 1 is a side elevation, partly broken away, of one species of apparatus comprising our invention; Fig. 2 is a vertical section through said apparatus along line 2—2 of Fig. 1 in the direction indicated, and with portions of the turret broken away to disclose tube gripping means, burners, and reshaping means at one end thereof; Fig. 3 is a side elevation of feeding and positioning means for the tubes; Fig. 4 is a section through one head of the turret, one of several movable burners, and means for actuating said burner along line 4—4 of Fig. 2; Fig. 5 is an end view of actuating means for the movable burners at one end of the tubes; Fig. 6 is a vertical section through the shaping means along line 6—6 of Fig. 2; Fig. 7 is a corresponding side elevation of the movable (right-hand) end of the apparatus; and Fig. 8 is a section through a center portion of the turret 12 along the line 8—8 on the turret 11 in Fig. 2.

The particular operation performed by the apparatus shown in the drawings is to reduce the diameter of a narrow section at both ends of the vitreous tube 10 and is brought about at a series of stations into which the tube 10 is advanced in turn by the vertical turrets 11 and 12. The turrets 11 and 12 function as a single

carrier as they are mounted on and keyed to the horizontal shaft 13 which provides for their indexing motion.

As shown in Fig. 1, the right end of the shaft 13 is supported on the ball bearing 14 in the housing 15 which rests on the rigid bed 16, and the left end of said shaft 13 is mounted in a similar manner in the larger housing 17 which is attached to the opposite end of the bed 16. In this particular instance, each head (indicated generally at 11' in Fig. 2) of the turrets 11 and 12 (which together may be termed a carrier) has associated therewith a roller 18 on the spider 19 on the end of the shaft 13 within the larger housing 17, and the indexing motion is brought about by a portion of the cam 20 which shifts said roller 18. Between indexing motions, a uniformly shaped portion of the cam 20 extends between two of the rollers 18 and holds the turrets or carrier 11, 12 in position. Such an indexing means is shown more in detail in Patent 2,021,001, J. F. Donovan et al., assigned to the assignee of the present invention. Movement of the cam 20, as well as all other parts of the apparatus, is under the control of a central driving means consisting of the shaft 21 which in turn is driven from the shaft 22 through the gears 23 and 24. Shaft 22 is preferably turned by an electric motor (not shown) enclosed within the bed 16 through the belts 25 and the pulley 26.

In their regular order of movement, the heads 11' are first indexed into station A at which the vitreous tubes 10 are fed thereinto. In this particular instance, the tubes 10 are of uniform diameter from end to end and are supported by the inclined rails 27 (Figs. 2 and 3) which cause them automatically to roll down into the openings 12' in the turrets 11' and 12 (which openings comprise portions of the heads 11') as rapidly as the heads are brought into alignment with the lower ends of said rails 27. The said rails 27 are mounted on the angularly shaped supporting bars 28 which are attached to the housing 17 and the movable brackets 29 surrounding the housing 15 and resting on the bed 16. The plates 30 on the outer sides of the rails 27 keep the tubes 10 from shifting endwise and roughly position said tubes 10 in the heads.

As the heads are indexed from station A, the tube 10 is first positioned longitudinally in the turrets 11 and 12, and is then engaged by gripping means thereon. The positioning of the tube 10 occurs as one end is carried against the resilient roll 28', in this instance made of sponge

rubber, and is pushed against the stationary stop 29' adjacent the opposite end of said tube 10 thereby. The roll 28' and the stop 29' are held in a fixed position by means attached to the housings 17 and 29 respectively and are separated a lesser distance than the length of the tube 10 so that the resiliency of the roll 28' must take up the additional length thereof. The gripping means of the turrets 11 and 12 comprises the jaws 31 and 32 which constitute portions of the heads 11' and are closed on the tube 10 by movement of the roller 33 away from the high part 33' of the stationary cam 34 surrounding the shaft 13. These jaws 31 and 32 are held in slide ways in the turrets below the cover plate 35, and are actuated through the pivotally mounted levers 36. One end of each of said levers 36 engages the slide 37 on which roller 33 is mounted, and the other end of each of levers 36 engages one of said jaws 31 and 32 through the blocks 38. The blocks 38 slide in ways in the jaws 31 and 32 and slide 37. The spring 39, which is largely contained within the well in the slide 37, forces said slide 37 toward the cam 34 so that the jaws 31 and 32 close on the tube 10 at this time, and it is kept from slipping out of position by the stud 40. The ring-shaped plate 41 which is mounted over the central opening in the cover plate 35 encloses the rollers 33 and the major part of the cam 34 which is prevented from turning therewith by a bar 42 attached at one end to the bracket 43 on the bed 16 and at the other end to the bracket 29. The cam 34 is supported by the shaft 13 which it engages through the ball bearing 44 (Fig. 4).

No operations take place at station B, and it is not until the tube 10 is indexed into station C that the ends thereof are heated by flames from the stationary circular burners 45 at either end. The burners 45, appearing in Figs. 1 and 2, are mounted beyond the ends of the tube 10 on pins extending from a circular disc 46 which in turn is mounted on one end of a tube 47 held by a bracket 48 on either bracket 29 or housing 17. The combustible gas mixture enters the burner 45 from a source (not shown) through the pipe 49. To prevent the heat transferred to the disc 46 from being in turn transferred to the machine, cooling water is circulated through the tube 47 from pipe 50 to pipe 51.

The heat from the burners 45 is not sufficient to soften the vitreous tube 10 in the short time interval allowed, and the next two indexing movements carry said tube 10 into stations D and E where it is heated further by the burners 52 and 53. The end of the tube 10 adjacent the left-hand end of the apparatus (as seen in Fig. 1) is, of course, treated by the particular burners 52 and 53 shown in Figs. 1 and 2, whereas the opposite end of the tube 10 is treated by the burners 52 and 53 mounted on the right-hand end of the apparatus as shown in Fig. 7. The burners 52 and 53 are of identical construction and, in order to avoid heating and softening more of the end portion of the tube 10 than is to be reshaped, are made so that they can be moved over the end of said tube 10. In said position, the burners 52 and 53 direct flames back toward the ends of said tubes 10 in a direction away from the tubes. More definite control of the flames is afforded in this manner and better heating action results as they do not meet and disturb each other.

In each case, the burner (52 or 53) comprises

a hollowed-out ring-shaped body portion 54 (Fig. 4) having a series of jets or openings 55 at an angle to the tube 10, and a cover plate 56 which closes off the chamber conducting the combustible gas mixture to the jets 55. The body 54 is mounted on three pins 57 extending from a circular plate 58 attached to the spindle 59 and is separated from the remaining mechanism by a shield 60 of asbestos or the like which keeps the heat therefrom. The shield 60 is mounted on the pins 57. Since the operations of both burners 52 and 53 at the opposite ends of the machine are alike, duplicate apparatus is provided at both ends for their operation. At either end the supporting spindle 59 for each burner 52 or 53 is mounted in the ball bearings 61 and 62 in a single cross head 63 which is fastened to the lower side of the slide 64. This construction enables the burners 52 and 53 to be moved to and from their operating position about the tubes 10, as the slide 64 has V grooves 64' (Fig. 5) at opposite sides which engage the ball bearings 65 held in the V grooves 66' of stationary gibs 66. The motion of the slide 64 is timed with the indexing motions of the turrets 11 and 12 by means of the cam 67 (Figs. 1 and 2) on the cam shaft 68 which is driven by the main drive shaft 21 through the bevel gears 69 and 70 and is the result of either the opening or closing of the electrical circuit to the solenoid 71 of each burner-moving mechanism. The solenoid 71, as shown, is mounted beyond the ends of the bars 72—72, located over each of the gibs 66, on the composite rubber and steel shock absorbing blocks 73 attached to the bracket 74 carried by said bars 72. The armature 75 of the solenoid 71 is connected to the block 76 on the adjacent end of the slide 64 and functions only when the burners 52 and 63 are to be pulled from their operating position to allow the tubes 10 to be indexed.

When the burners 52 and 53 are carried into operating position, the circuit to the solenoids 71 is broken by a change in shape of the cam 67 which shifts the roller 77 and the arm 78, causing the switch 79 to be actuated, said switch controlling both solenoids 71. The spring 80, which extends from a well 81' in the fastening 81 on the forward end of the slide 64 to the cross arm 82 extending between the bars 72, now expands and moves the slide 64. The said spring 80 surrounds a rod 83 which extends from the cross arm 82 and slides in said fastening 81. Since the movement of the slide 64 is quite rapid, a dash pot is provided in the block 76, and a piston 84 resting against the spring 80 and blocking the opening, is caused to strike the cross arm 82 when the limit of motion is reached. The air behind the piston 84 is bled out through the passage 86. The return movement of the slide 64 and the burners 52 and 53 occurs as the switch 79 is closed and the armature 75 is drawn into the solenoid 71.

As shown, the spindle 59 supporting each burner 52 or 53 has an axial passage 87 therein which communicates with the chamber distributing the combustible gas to the jets 55 through the passages 88 and 89 located, respectively, in a flange 59' on spindle 59 and in the pins 57. The passage 87 terminates in a cap 90 on the end of said spindle 59, which cap is connected by the pipe 91 to the source of the combustible gas. In addition, two other passages 92 and 93 are provided in the spindle 59 for conducting cooling water to and from the chamber 94 located between a flange 59'

on said spindle and the circular plate 58. These passages 92 and 93 terminate in the circular passages 95 and 96, respectively, in the spindle 59, the sleeve 97 surrounding said spindle and the cross head 63. Said passages 95 and 96 permit the cooling water entering through pipe 98 (Fig. 5) and draining through pipe 99 respectively to service the cooling means.

Since considerable heat is transferred to the turrets 11 and 12, each is cooled by the circulation of water in the passage 100 in the outer face thereof between the dotted lines 100' and 100'' in Fig. 2. The cooling water is conducted to and from the passage 100 in each instance by pipe connections on opposite sides of the inside face of the turret which in turn is connected through a flexible hose 101 and pipe nipple 102 to either of the longitudinal passages 103 and 104 in the shaft 13. The passages 103 and 104 (Fig. 1) extend the full length of the shaft 13 and terminate in the grooves 103', 104' in the right end thereof which are serviced by the apertures 106' and 107' in the stationary block 105. The block 105 is a stationary member connected to the water supply through pipe 106 and to a drain through pipe 107, and is held in place on the shaft 13 by the cap 108.

To assure uniform heating by the burners 52 and 53, each is rotated by means of the gear 109 attached to the back of the flange 59' on the spindle 59. The gears 109—109 of each pair of burners 52 and 53 mesh together and are driven through a stationary wide-face gear 110 mounted on the drive-shaft 111 of the speed reducer 112 carried by the electric motor 113 which in turn is mounted on the plate 114 bridging the gap between the bars 72. The width of gear 110 is sufficient to permit one of the gears 109 to mesh with it when the burners 52 and 53 are advanced and retarded, so that they are rotating at all times.

The heat transferred to the ends of the tube 10 at stations C, D and E is sufficient to bring them to a plastic state and, when said tube 10 is indexed into station F, shaping means work said ends to the form desired. The shaping means, which is duplicated at both ends of the apparatus, is shown in Figs. 1, 2, 6 and 7 and comprises a centrally positioned roll 115 and three rolls 118 spaced thereabout. Roll 115 is mounted on the circular cover plate 116 on the end of the hollow spindle 117 and is moved into the open end of the tube 10. The rolls 118 move radially inward and press a narrow band of the tube 10 adjacent its rim into contact with the center roll 115. Each of the outer rolls 118 is mounted on a slide 119 extending through a slot in the cover plate 116 and operating in ways in the spindle 117 which at the start of the cycle of operation is drawn back to keep the rolls 115 and 118 away from the end of the tube 10. The spindle 117 rides in the ball bearings 120 and 121 in the slide 122 and is moved into operating position by cam 123 on the cam shaft 68 which engages the roller 124 extending from the lower part of said slide 122. Slide ways are provided for slide 122 by ball bearings 125 at both sides which ride in grooves in slide 122 and gibs 126 held by the bracket 127 which is attached to the housing 17 and encloses the cam 123.

At the moment the rolls 115 and 118 are moved into operating relation to the tube 10, the slide 128 which is located directly behind slide 122 is also moved forward by the cam 129 which it engages through the roller 130. The slide 128 func-

tions as the operating means for the rolls 118 in that it positions the rod 131 which engages the actuating levers 132 for each of the slides 119. The levers 132 are mounted on a pin 133 passing through a slot in the spindle 117 in which they are located and engage slide 119 and rod 131 through the blocks 134. The slide 128 does not engage rod 131 directly, but through ball bearing 135 which permits said rod 131 to turn with the spindle 117. Once the roll 115 has entered the end of the tube 10 and the rolls 118 have moved over the portion of the rim of said tube 10 to be reshaped, the motion of slides 122 and 128 in a forward direction stops and a backward movement of the slide 128 occurs. This motion pulls the rolls 118 radially inward against the tube 10 which is pressed against the center roll 115 and takes the form shown. At this time, the rolls 118 are being rotated about the tube 10 by motion of the spindle 117 which is driven from the shaft 136 (Figs. 1 and 2) through the spur gears 137 and 138. The shaft 136 is held by the bracket 139 attached to the housing 17 and in turn is driven by the electric motor 140 through a pair of speed reducing gears (not shown) contained within said housing. This construction causes the entire periphery of the end of the tube 10 to be treated in a like manner and, together with the other apparatus which assures positive alignment of the shaping means with tube 10, causes said end portions to be uniformly and concentrically formed.

In the return of the shaping means, slide 128 is first moved forward to separate the outer rolls 118 from the tube 10 and then both slides 122 and 128 are moved backward together to carry the rolls 115 and 118 out of the path of movement of the tube 10.

The next indexing movement of the turrets 11 and 12 carries the tube 10 into station G which is provided to allow the ends thereof to cool, and the succeeding indexing movement carries said tube 10 into station H where it is released by the jaws 31 and 32 and drops from said turrets 11 and 12. The indexing motion carries the roller 33 of the jaw operating means onto a second raised portion 33' of the cam 34 which actuates the jaws 31 and 32. In this particular instance, the reshaped tube 10 falls onto the moving belt 141 and is quickly carried to suitable annealing means.

One of the particular advantages of the apparatus shown is the ease with which it can be adjusted to accommodate different lengths of tubes. This advantage is made possible by mounting all the burners 45, 52 and 53 and the reshaping means at the right end of the apparatus on the housing 29 which can be adjusted longitudinally with respect to the shaft 13 on the bed 16. The housing 29 is clamped to the bed 16 by suitable means (not shown) when in use and is adjusted, after said clamping means is loosened, by rotation of the crank 142 on the end of the screw 143. The screw 143 engages threads in the housing 29 and is held in place by the bracket 144 at one end and the bracket 145 at the other. Since it is desirable that the end of the tube 10 adjacent the right end of the apparatus be positioned accurately by the turret 12, said turret is slidably mounted on the shaft 13 and is adjusted therealong an amount corresponding to that given in the housing 29. Such adjustment is brought about by connecting the turret 12 to said housing 29 by means of the ring 146 on said housing

29 which overlaps the collar 147 on said turret 12. A series of openings in the shaft 13 leading to the passages 103 and 104 therein permits the cooling means for the turret 12 to be attached thereto at various places. The unused openings are plugged by easily removable plugs which do not interfere with the adjustment of the turret 12.

Figs. 2 and 8 illustrate the overlapping construction of the ring shaped plate 41 of the turret 12 which causes the cam 34 to move longitudinally on shaft 13 when the position of the turret 12 is adjusted.

What we claim as new and desire to secure by Letters Patent of the United States is:

1. Apparatus for reshaping the ends of a vitreous tube comprising gripping means for holding and positioning the tube, a carrier for supporting said gripping means and advancing said tube into each of a plurality of stations in turn, burners located at a plurality of stations for heating the ends of the tube to a plastic condition, independent actuating means for moving at least one of said burners at each end of the tube to and from operative relation to the corresponding tube end as it is indexed into the station occupied by the burner, means for rotating said last-mentioned burner to cause it to heat the ends of the tube evenly, and means located adjacent said carrier at a succeeding station for reshaping said ends.

2. Apparatus for reshaping the ends of a vitreous tube comprising a carrier having heads at spaced intervals thereon, means for indexing said carrier to advance said heads to a plurality of stations in turn, means for introducing a tube in said heads at one of said stations, means located along the path of movement of said heads for positioning the tubes longitudinally therein comprising a stop member adjacent one end of a tube in one of said heads and a resilient roll in the path of movement of the opposite end of said tube for pushing said tube against said stop member.

3. Apparatus for reshaping the ends of a vitreous tube comprising a plurality of turrets mounted in spaced relation along a horizontal axis, corresponding gripping means in alignment with each other on said turrets for supporting and holding a tube intermediate its ends so that said ends project freely therefrom, means for indexing said turrets corresponding amounts to advance the tube to a plurality of stations in turn, and means located adjacent said turrets for heating and reshaping the freely projecting ends of the tube at said stations.

4. Apparatus of the class described for simultaneously reshaping both ends of vitreous tubes comprising a rotatably mounted carrier having means at its periphery for gripping a tube intermediate its ends so that the ends of the tube project freely therefrom, means for indexing said carrier to carry the tube through a definite path of travel, heating and reshaping mechanisms arranged adjacent the path of travel of one end of said tube to heat and reshape said end, means for actuating said reshaping mechanism, fixed support means carrying said heating and reshaping mechanisms and said actuating means, and a second set of heating and reshaping mechanisms arranged adjacent the path of travel of the other end of said tube to heat and reshape it with actuating means for said second-mentioned reshaping mechanism wholly independent of the actuating means for the first-mentioned reshaping mechanism, and movable support means carrying the second-mentioned

set of heating and reshaping mechanisms and its associated actuating means so as to be bodily movable toward or away from the first-mentioned support means and the mechanisms carried thereby.

5. Apparatus of the class described for simultaneously reshaping both ends of vitreous tubes comprising a rotatable carrier mounted on a shaft and having means at its periphery for gripping a tube intermediate its ends so that the ends of the tube project freely therefrom, means for indexing said carrier to carry the tube through a definite path of travel, heating and reshaping mechanisms arranged adjacent the path of travel of one end of said tube to heat and reshape said end, means for actuating said reshaping mechanism, fixed support means carrying said heating and reshaping mechanisms and said actuating means, and a second set of heating and reshaping mechanisms arranged adjacent the path of travel of the other end of said tube to heat and reshape it with actuating means for said second-mentioned reshaping mechanism wholly independent of the actuating means for the first-mentioned reshaping mechanism, and movable support means slidable alongside the said shaft and carrying the second-mentioned set of heating and reshaping mechanisms and its associated actuating means so as to be bodily movable toward or away from the first-mentioned support means and the mechanisms carried thereby.

6. Apparatus of the class described for simultaneously reshaping both ends of vitreous tubes comprising a rotatable carrier mounted on a shaft, said carrier comprising a pair of spaced turrets having corresponding aligned gripping means at their peripheries for holding a tube intermediate its ends so that the ends of the tube project freely therefrom, one of said turrets being fixed to said shaft and the other being slidable along said shaft, with means for securing said slidable turret to said shaft, means for indexing said carrier to carry the tube through a definite path of travel, heating and reshaping mechanisms arranged adjacent the path of travel of one end of said tube to heat and reshape said end, means for actuating said reshaping mechanism, fixed support means carrying said heating and reshaping mechanisms and said actuating means, and a second set of heating and reshaping mechanisms arranged adjacent the path of travel of the other end of said tube to heat and reshape it with actuating means for said second-mentioned reshaping mechanism wholly independent of the actuating means for the first-mentioned reshaping mechanism, and movable support means slidable alongside said shaft and also connected to the adjacent slidable turret and carrying the second-mentioned set of heating and reshaping mechanisms and its associated actuating means so as to be bodily movable toward or away from the first-mentioned support means and the mechanisms carried thereby.

7. Apparatus of the class described for simultaneously reshaping both ends of vitreous tubes comprising a carrier mounted to rotate on a horizontal axis and having means at its periphery for gripping a tube intermediate its ends so that the ends of the tube project freely therefrom, said gripping means securely holding said tube against rotation about its own axis, means for indexing said carrier to carry the tube through a definite path of travel, duplicate sets

of burners and reshaping mechanisms arranged adjacent the paths of travel of the ends of said tube, each of said sets of burners comprising a ring-type burner with its jets arranged to project a conical flame, means for reciprocating said burner to move it over and slightly beyond the adjacent end of the tube after the tube has been indexed into a position opposite the burner to cause the flame from the burner to be directed

back onto the end of the tube, and each of said sets of reshaping mechanisms comprising forming members, means for rotating said forming members, and means for reciprocating said forming members to move them into engagement with the adjacent end of the tube to reshape it.

CLARENCE E. HAHN.
JOHN SALO.
